(57) **CLAIM**

The ornamental design for a hitch, as shown and described.

DESCRIPTION

FIG. 1 is a perspective view of a hitch shown in a position of use.

FIG. 2 is a front perspective view thereof.

FIG. 3 is a rear perspective view thereof.

FIG. 4 is a front view thereof.

FIG. 5 is a rear view thereof.

FIG. 6 is a left side view thereof.

FIG. 7 is a right side view thereof.

FIG. 8 is a top view thereof; and,

FIG. 9 is a bottom view thereof.

The design is for a hitch which is adapted to be connected to the rear of a motor vehicle. The hitch, in use, receives a ball mount and a hitch ball.

The broken lines within the solid lines in FIG. 1 and all broken lines in FIGS. 2-8 illustrate portions of the hitch that are not included in the claim. All other broken lines in FIG. 1 depict environmental subject matter that forms no part of the claimed design.
